TREATING SKINS, TEXTILE FABRICS, AND
THE LIKE

Paul Poser, London, England

Application May 16, 1946, Serial No. 670,188
In Great Britain May 16, 1945

7 Claims. (Cl. 69—31)

1

This invention relates to the treating, as by washing, bleaching, dyeing, waterproofing, and complete or partial drying, of fur skins, skivers, small hides, and textile materials (all of which are hereinafter referred to as "skins"), and my object is to provide an improved method of and apparatus for these purposes whereby the treatment can be carried out efficiently under complete and continuous control in a rapid, safe, and clean manner, with a minimum of risk of toxic injury to the operator and of the need for handling the skins. For convenience of description the term "reagent" is used, in the following description, to denote any appropriate liquor employed in treating the skins.

According to this invention the method of treating skins consists of the following steps, (a) arranging a number of skins in a stack within an hermetically-sealed chamber, (b) circulating the appropriate reagent across the chamber in a direction which is substantially parallel to the planes of the individual skins, (c) causing different portions of the peripheries of the skins in the stack to be presented to the flow of the reagent (e. g., by maintaining a steady reagent flow and moving the stack with reference thereto, or by maintaining the stack stationary and reversing the direction of reagent flow), (d) subjecting the skins to continuous flexure and repeated alternations of pressure increments in different parts in a direction transverse to the reagent flow so as to force the reagent intimately into the substance of the skins, (e) controlling the temperature of the reagent, and (f), after withdrawing the reagent, drying or partially drying the skins in the chamber.

The method may include the further steps of initially exhausting, of air, the chamber in which the skins are to be treated so as to secure better penetration of the reagent, and of exhausting the said chamber after any processing step has been completed so as better to remove any reagent which is wetting the skins. The method may include the circulating of heated air to facilitate oxydising and drying the skins.

According to a further feature of the invention, the apparatus for carrying out the improved method includes a chamber in which the skins are to be placed in a stack, a header tank for a reagent to be used in the treatment, means for controlling the reagent flow at a varying speed and pressure through the chamber and the stack of skins, the latter to be so arranged that the planes of the individual skins will be substantially parallel to the direction of the said flow,

2

means for causing different portions of the peripheries of the skins in the stack to be presented to the flow of the reagent, means serving for repeatedly and alternately applying pressure increments to different areas of the skins, in a direction generally normal to the fluid flow, such means also serving for flexing the skins continuously at the same time, valve means for controlling the flow of the reagent, and thermostatically-controlled heating means for the reagent.

10 The change of direction of the reagent flow with reference to the skins may be effected by providing the chamber with two alternative inlet duct means at two opposite ends of the chamber, 15 and two alternative outlet ducts at the said opposite ends of the chamber, valve means being provided for selectively including one of each of the alternative ducts in a closed circuit, including a pump, for the reagent.

20 These inlet duct means may be in the form of single ducts, or they may be groups of ducts or injectors, spaced apart, so as to secure a relatively wider distribution of the pressure-flow through the skins. It is preferred, in either case, 25 for there to be only two alternative outlet ducts although, obviously, more could be provided according to the distribution of pressure-flow required. Alternatively, the chamber may have one inlet and one outlet, oppositely arranged, and a 30 reversible pump be employed. Or, again, the chamber may have one inlet and one outlet, and the stack of skins may be rotated so that the relative direction of reagent flow is constantly 35 changed, a non-reversible pump being used in this case. The chamber can be of any suitable shape and the flow of reagent be arranged to take place vertically or horizontally in the chamber.

40 Preferably, the apparatus embodies a working chamber which is rotatively supported so that different phases of a compound treatment (by which I mean a treatment including a plurality of steps, some of which, possibly, require a different reagent, and others, possibly, consisting of 45 a drying or partial drying of the skins) can be carried out with the chamber stationary, rotating relatively-slowly, or rotating at a relatively-high speed, as appropriate. The chamber, also, will preferably have inlets and/or outlets, for 50 the reagent and for air. The apparatus will also, preferably, be capable of being heated to a desired temperature, as necessary, under thermostatic control, it will have means for controlling the quantity and pressure of the reagent-flow, and 55 for indicating and recording physical data (such

as temperatures, pressures, time-periods) of the treatment.

Thermometers, heaters, and flow-meters, can be provided, as necessary, for the reagent in different positions in the circuit.

Provision is preferably made for charging the aforesaid header tank with alternative reagents through a pipe provided with a stop valve and connected to a chemical mixing chamber. Hot water can be supplied from a cistern, through a stop valve, to the mixing chamber where the reagents can be mixed to the desired concentration. The mixing chamber, the header tank, or both, may be heated.

According to a still further feature of the invention the chamber, for the skins to be treated, has a resiliently compressible internal bed at one side, and at least a pair of pistons at another side spaced apart and adapted alternately to act on the skins (either directly or by means of pressure waves set up in the reagent) in conjunction with the said bed for squeezing, releasing, and flexing different parts of the skins so as to cause the reagent to flow intimately into their texture.

Various forms of apparatus, according to the invention, are described below, by way of example, in conjunction with the accompanying drawings. In these latter:

Figures 1 and 2 show, diagrammatically, a side elevation and plan, respectively, of one form of apparatus, some of the piping being relatively displaced in the two views for ease of illustration;

Figure 3 is a part-sectional elevation, to an enlarged scale, of the skin-containing chamber and other parts of the apparatus shown in Figures 1 and 2;

Figure 4 is a side elevation, corresponding to Figure 1, but showing the apparatus encased and with one form of control board with which it can be provided;

Figures 5 and 6 are, respectively, a section, (taken on the line 5—5 of Figure 6), and a sectional plan of another form of skin-containing chamber incorporating a modified arrangement for applying pressure increments to the skins and for relieving the said pressure increments;

Figure 7 is a diagram, showing in sectional elevation, another form of the apparatus, various of the components, however, being displaced from their proper positions to facilitate the description of the hydraulic and pneumatic circuits;

Figure 8 is a sectional elevation of the apparatus illustrated by Figure 7, but showing the components in their intended positions, the section being taken on the line 8—8 of Figure 9;

Figure 9 is a part-sectional plan, corresponding with Figure 8, the portion in section being taken on the line 9—9 of Figure 10; and

Figure 10 is a front elevation of the apparatus illustrated by Figures 7 to 9, showing the instrumentation and controls.

The apparatus shown in Figures 1 to 4 comprises a chamber, generally indicated at 21, for the skins, a water tank 22, a mixing chamber 23, and a header tank 24 for the reagent. Of these components, which are operatively associated in the manner hereinafter described, the chamber 21 is supported on a pedestal 25, whilst the others are supported by a pair of horizontal frame-members 26 (one only of which is shown)—the header tank by the brackets 27, the mixing chamber by the stretchers 28, 28a, and the tank 22 by the stretchers 29. The frame-members 26 are supported by pairs of uprights, one pair being constituted by downward extensions of the stag-

ing members 28a and the others being shown at 31. The aforesaid components, and others to be hereinafter referred to, are arranged compactly, as indicated in Figures 1 and 2, and encased as shown in Figure 4, additional frame-members, such as the uprights 32 and horizontals 33 (see Figure 1) being provided for the attachment of the casing panelling 34.

The water tank 22, which may incorporate any suitable heating means, such as steam coils, but, preferably, an electrical heater (not shown), has an inlet pipe 35 provided with a stop-cock 36, and an outlet pipe 37 which communicates, through a stop-cock 38, with the mixing chamber.

The mixing chamber is shown as having a closable charging opening 39, a stirrer 40 to be driven by an electric motor 41, and an outlet pipe 42 to the header tank, the outlet being controllable by the stop-cock 43. It also has the actuating elements of a quantity meter and of a pH indicator, indicated, respectively, at 44 and 45, which are preferably of a type which will give remote readings on a control panel as hereinafter described.

The header tank 24 has an hermetically-sealing, removable, lid 46 which may be of any suitable kind but which, as shown, is hinged at 47 to the tank and provided with a toothed quadrant 48, for coaction with a pinion 49 to be driven by an electric motor 50, for raising the lid to the dotted line position, shown in Figure 1, and for lowering it. The motor 50 is shown as being supported on a bracket 51 secured to the uprights 28a. The header tank is connected to a pump, hereinafter described, for circulating the reagent, by a down-take pipe 52, through a stop-cock 53, and by an up-take pipe 54. It also is provided with an automatic air-lock eliminator, indicated at 55 in Figure 3.

The chamber 21 is provided with a removable, hermetically-sealing, cover 56, which may be adapted to be opened and closed in any suitable manner, but preferably by a quadrant 57 and pinion 58, driven by an electric motor 59. The cover 56 has a lower cylindrical portion which registers, when the cover is closed, with the inside of a ring 60 fast with the chamber, and a piston-like lower wall 61 is guided, in an hermetically-sealing manner, in the said cylindrical portion and ring. The wall 61 can be raised or lowered by a screw 62 and worm gear 63 driven by an electric motor 64 mounted on the cover. When it is desired to open the cover, the wall 61 has first to be withdrawn into the cover, the motors 59 and 64 being electrically interlocked so that the two movements take place in proper sequence. The wall 61 incorporates two rams 65 which can, in the example given, be reciprocated by connecting rods 66 and disc cranks 67, one of these latter being geared to be driven by electric motor 68 and the other through chain gearing 69. (Obviously, however, there may be more than two rams, and in this case their respective crank discs can be geared to be driven by the motor 68.) The rams may work in unison, but will preferably be out-of-phase. The purpose of these rams is to produce pulsations in the reagent, and their speed of reciprocation is preferably automatically adjustable to the rate of reagent-flow through the chamber (hereinafter described) so as to ensure that no cavitation takes place. The chamber 21 contains a perforated cylindrical basket 70 which is removably mounted on a central shaft 71 and provided with a fine-mesh gauze lining 72. On the perforated bottom plate of the bas-

ket is placed a bed 72 of resilient material, such as sponge rubber or air-filled rubber balls, which will react to the pulsations caused by the rams 65. The shaft 71 extends through an hermetically-sealing gland 73, journal bearings 74, and an oil seal 75, and carries a coupling 76 (which may be of the centrifugal slipping type) to an electric driving motor 77. The shaft is located by a thrust bearing 74a.

A sealing ring 78 of the wall 61, when the latter is in its lowered position, makes hermetical sealing contact with the upper end of the basket 70, which end is flanged inwardly for this purpose, and axially-arranged baffles 122 (see Figure 6) are preferably disposed between the basket and the wall of the chamber so as to prevent short-circuiting of the reagent.

The pipes 52 and 54 connect the top and bottom of the header tank, through stop-cocks 79 and 80 respectively, to a reversible, variable-quantity, pressure pump 81 which may be of the type which has plungers operated by eccentrics mounted on a driven shaft, or of other suitable type. The pump is to be driven by an electric motor 82. The quantity and pressure of the pump output can be governed, by an electric relay, from the control panel. The pipe 52 is connected to the chamber 21 through a reducing valve 83, and the chamber is also connected, by pipes 84 and 85, to the pump 81, through stop-cocks 86, 87, respectively. The pipes 84 and 85 are also connected to pipes 110, 111, respectively, leading to opposite sides of the chamber 21. The reagent-flow circuit is hermetically sealed throughout and all air or other gases are removed by the automatic air-lock eliminator 55 of the header tank.

During some one or other of the treatments, the reagent in chamber 21 may be absorbed by the skins, and valves are arranged so that the said chamber will always be full. These valves comprise a float valve 88, the reducing valve 83 (which is to be set to maintain the desired pressure in chamber 21), a safety valve 89 to return excess pressure to the header tank 24 through the pipes 90 and 54, and an overflow valve 91 which leads to a filter hereinafter described. With stop valves 79 and 80 closed the header tank is isolated from the pump, and with the latter working a constant circulation of reagent through chamber 21 is obtained. By reversing the pump the direction of circulation can be reversed. A drain-cock 92 is fitted to the bottom of the chamber 21 and is connected by a pipe 93 to a combined reagent-filter and fat-separator 94, a pipe 95, leading from the overflow valve 91, joining the pipe 93 at 95. The separator is connected by a pipe 97 to an exhauster 98, to be driven by an electric motor 115, for expelling intoxicated air, and by a pipe 99 to a pump 100, to be driven by an electric motor 116, for returning filtered and purified reagent to the header tank through the pipe 101 and stop-cock 102.

An air compressor 103, which is arranged so as also to function as a vacuum pump, is driven by an electric motor 104, and the discharge pipe 105 of the compressor is connected through pipes 106 and 107, with stop valves 108 and 109, respectively, to the inlets 110, 111, of the chamber 21. An air relief valve 112 is fitted in the wall 61 of the cover 56 and the latter has air escape holes, one of which is shown at 113 in Figure 3. The intake for the compressor has a filter 114. Alternatively, an external source of compressed air could be used.

By setting the various stop-cocks, as follows, the following conditions can be obtained:

(a) *All stop-cocks closed.*—Chamber 21 shut off completely from reagent and air.

(b) *Stop-cocks 86 and 87 open.*—Flow of reagent only through the chamber from left to right, or from right to left, according to the direction in which the pump 81 is set to operate.

(c) *Stop-cock 103 or 109 open.*—Flow of air only from right to left, or left to right, respectively.

(d) *Stop-cocks 86 and 109 open.*—Flow of reagent combined with compressed agitating air from left to right.

(e) *Stop-cocks 87 and 103 open.*—Flow of reagent combined with compressed agitating air from right to left.

(f) *Stop-cock 103 or 109 open and compressor 103 acting as a vacuum pump.*—Maintenance of vacuum in chamber 21.

Remote indicating and recording flow meters 117, of Venturi type or the like, are fitted in flow pipes 52, 54, 110, and 111 to and from chamber 21, and thermostatically-controlled heating elements 118 (which may be electrically or steam-operated) are provided for the said pipes and in air pipes 106, 107, so that the circulating reagent, or air, or both, can be raised to the desired temperature. The circulating pipes 110, 111 where they enter the chamber 21, may be bell-mouthed or flared, as shown, or, alternatively, they may be divided into a number of multiple jets. Actuating elements, for remote reading quantity and pH indicators 44, 45, similar to those of the mixing chamber are provided for the header tank, and a pH indicator is provided for the chamber 21, the quantity meters preferably being of the type having floats for making contact on electrical resistances. Sockets 119 and 120 for remote reading thermometers and remote reading pressure indicators, respectively, are fitted in the chamber 21 and the header tank 24. The transmission for all of these instruments to the control panel is electrical.

All of the electric motors embodied in the apparatus are arranged for alternative automatic remote control through a master time switch 123, or hand control through remote push buttons 124, these switches being on the control panel—see Figure 4. The opening and closing of all stop-cocks can also be effected automatically through the master time switch 123, or hand remote control through separate switch levers 125 fitted with indicators.

Remote-control thermostatic regulators 126, for the various heaters are provided on the control panel, and these may work on the principle of differential expansion, or the like, operating relays which control mercury-tube switches governing the electrical energy input to the heaters 51, these regulators incorporating thermometers for indicating and recording the temperatures due to the heaters.

The panel also has indicating and recording thermometers 127 to give an independent check of the temperatures in the chamber 21 and the header tank 24. Indicating and recording flow meters 128 (connected to the flow meters 117) and indicating and recording pressure gauges 129 (connected to the chamber 21 and the header tank 24, respectively) are provided on the panel. The latter also has quantity meters 130 and pH meters 131, connected to the actuating elements 44, 45, respectively, of the mixing and header tanks and the chamber 21, as appropriate.

The electric motors 77 and 82 (for driving the basket and the reagent pump, respectively) preferably incorporate tachometers 132, which have remote-reading dials 133 on the panel.

All of the meters on the panel can be of any suitable known type.

The chamber 21 and the header tank may have inspection windows 134 and means for giving an audible warning when the fluid level is too low.

The master time switch 123 is geared to close and open electrical circuits in a predetermined sequence, and at predetermined intervals, so as to operate the electric motor starters and the stop-cocks (through electrical relays where necessary), and also to supply current to the heater elements 113 and a heater for the water tank 22 if required. The master time switch contact-makers are adjustable to enable the timing and order of the cycle of operations to be varied, so that, for instance, the chamber 21 could be exhausted, the skins could then be treated, for different purposes, by say, three different reagents, each such treatment being preceded by a washing step, the basket being retained stationary, or rotated slowly, and the direction of reagent flow through the chamber being maintained in one direction, or reversed, as requisite or desirable. The skins could then be centrifuged, by rotating the basket at a relatively-high speed, and finally air dried.

The basket can be provided with hooks, or the like (not shown), so as to enable it to be lifted out of the chamber 21, by a crane, to facilitate charging it with skins and removing them.

As an alternative to circulating the reagent and air as above described, the respective pipes could be connected to the bottom and top of the chamber 21 so that the flow is vertical, in which case the upper pipe for the reagent would pass through the cover 56 and be flexible. With such a construction and as shown in Figures 5 and 6, the reciprocating rams 65a would be arranged horizontally and be operated by crank discs 67a, vertical shafts 135 and pinions 136 (one only of which latter is shown), and the pinions would engage with a ring gear 137. The ring gear is driven by a pinion 138 on the shaft of an electric motor 139, the speed of the motor being capable of adjustment to give the required conditions.

It may, in some instances, be decided to carry out certain treatments with the cover 46 open, and the float valve 88 and overflow 91 will allow this to be done.

Referring now to the apparatus illustrated by Figures 7 to 10, there is a stationary cylindrical outer tank 140 and a rotary inner cylindrical basket-like tank 141 into which latter the skins are to be placed in a stack. The tank 141 has an annular rubber cushion 142 (filled with air or springs), at the bottom, surrounding a central platen 143, and the cushion and platen are covered by a soft rubber sheet 144. The tank 141 can be rotated, through a worm-wheel 146 and worm 147, by an electric motor 148 which can drive the worm through either of two alternative gear pairs 149 and 150, or 151 and 152, contained in a gear box 153, so as either to drive the tank slowly or quickly. The platen 143 has an axial shaft 154 carrying, at the bottom, a cam disc 155 which can coact with a cam track fast with the stationary tank 140 so that, as the tank 141 rotates, the platen will be reciprocated vertically. The worm-wheel is fast with the hollow shaft 201, which, in turn, is fast with the bottom of the tank 141, and the shaft 154 is splined, or

otherwise relatively-non-rotatably but slidably held in the shaft 201.

The tank 141 has a removable lid 156 carrying two or more rams 157 which are preferably covered with soft rubber and which are spring-biased into their upward positions. The tank 140 has a lid 158 hinged to it at 159 and provided with clamping devices 160 to hold it closed in an hermetically-sealing manner. The lid 158 has a pair of annular cams 161 into contact with which the pairs of supporting stems 162 of the rams 157 are urged by their springs. Thus, during rotation of the tank 141 the rams 157 are reciprocated and, together with the cushion 142 and the platen, cause vertical pulsations and flexing of the skins so as to promote intimate contact with the latter, of the reagent being used.

The lid 158 is provided with a cable 163 which is passed over a pulley 164 and secured to a winding handle 165 for raising and lowering the lid.

Beneath the tanks 140 and 141 is a transfer tank 166, and this last-mentioned tank communicates with the tank 141 through the passage 167, the tank 141, in turn, communicating with a bulge 168 in the tank 140.

A header tank 169, provided with a charging opening 170 for the reagent, with a water supply pipe 193 having a stop-cock 194 and controlled by a float-operated valve 195, and internally heated as by steam pipes 171, communicates, through a stop-cock 172 and pipe 173, with the tank 166, which latter may be provided with a thermostatically-controlled heating element 174 to maintain, or adjust, the temperature of the reagent.

The steam coil 171 is fed from a supply pipe 188 having a stop-cock 189 and a valve 190, the amount of opening of the latter being subject to control by the thermostat 191.

The tank 166, into which the reagent from the tank 141 also flows, discharges through a pipe 175 and coarse and fine filters 176, 177, respectively, to the intake of a pump 178. This pump is of any suitable type and is driven by an electric motor 179. The pump delivery pipe 180 includes a three-way valve 181 which can, according to its setting, interrupt the circuit, deliver reagent through the pipe 182 to the aforesaid bulge 168 so as to cause a pressure flow through the stack of skins, or deliver used reagent through the pipe 183 to a sewer or diluting tank, not shown.

A compressor-exhauster 184 driven by an electric motor 192 and having its compressor side delivery, say, at the left of Figure 7, and its exhauster side intake at the right of that figure, communicates alternatively, through one of two two-way valves 185, 186, with a pipe 187 leading to the aforesaid bulge 168. A stop-cock 30 is provided between the connections of the opposite sides of the compressor-exhauster to the pipe 187.

According to the setting of the valves 185 and 186, reagent can be induced from the header tank 169 into the tanks 140, 141, and 166 or, with the valve 181 suitably adjusted, compressed air can be delivered to the tanks 140, 141, and 166 for clearing the reagent from the system and passing it into the sewer or diluting tank. The stop-cock 172 and the valves 181, 185, and 186 are preferably electro-magnetically operated, and, together with the heaters, the pump, and the compressor-exhauster, are subject to control by a time-switch and, separately, by individual manually operated switches. These switches (which

are not shown) can conveniently be on a control panel mounted on the front of the header tank. On this panel are also the indicating and recording portions 196 of thermometers the temperature-sensitive portions of which are disposed where necessary or desirable, one or more pH indicators 197, reagent flow-meters 198, and a process indicator 199. The header tank and the tank 140 are preferably provided with liquid-level indicators 200.

In operation, when the tank 141 has been filled with skins, the lids 156 and 158 are closed, and the tank 141 caused to revolve at slow speed. The compressor-exhauster exhausts air from the tanks 140, 141 and 166, and the lid 158 is then tightened down by means of clamps 160. When the header tank has been filled with water, to which any necessary chemicals have been added, and has reached the process temperature, the valve 172 is opened to allow its contents to flow into tanks 166, 141 and 140. The valve 172 is then closed, and the header tank refilled ready for next process-step. The pump 178 is then started up and forces the reagent into the bulge 168 and through the tank 141. The reagent is thus forced between the skins (which are pulsating, flexing, and revolving with the tank) in intimate contact, the reagent then passing through the ports 167 into the tank 166 for further circulation. On the completion of each process-step, the three-way valve 181 is opened to sewer or diluting tank, the pump 178 is stopped, and the compressor-exhauster caused to eject all of the reagent from tanks 140, 141 and 166 to the sewer or diluting tank. The tank 141 is now driven at high speed and the reagent wetting the skins centrifuged away, thus partly drying the skins. After the removal of the reagent has been completed, the compressed air valve 185 is returned to normal, and the compressor-exhauster caused to exhaust all air from the system preparatory to carrying out the next process-step, if any.

In carrying out a complete treatment, the individual processes, such as cleaning, washing, dyeing, water-proofing, etc., are carried out in the desired order, it being only necessary for the operator to add the essential chemicals into the header tank 169 as indicated on the process indicator 199. All fumes and gases are removed from the apparatus on ejection of the reagents, thus safeguarding the operator's health and giving healthier working conditions. The skins can be finished in an almost dry condition and require very little drying.

In a modified form of the apparatus of Figures 7 to 10, the basket-like tank 141 is not rotatable and the pump 178 and the compressor-exhauster 184 are either made reversible or connected to the said tank through reversing-valve means so as to enable the direction of reagent flow and air flow through the tank to be reversed. In this case the rams 157 would be driven by an independent mechanism such, for instance, as by a mechanism similar to that described with reference to Figure 3. All parts of the apparatus which come into contact with the reagent may be made of appropriate corrosion-resistant metal, or of metal protected by enamelling, plating or a covering of rubber, ebonite or other suitable substance, as appropriate.

What I claim as my invention and desire to secure by Letters Patent of the United States is:

1. Apparatus, for use in treating skins, com-

prising a chamber in which the skins are to be placed in a stack, a header tank for a reagent to be used in the treatment, means for propelling the reagent through the chamber in a direction from edge to edge of the skins in the stack, means for controlling said propelling means to vary the speed and pressure of the reagent flow, means for relatively presenting different portions of the peripheries of the skins in the stack to the reagent at entry to the chamber, means for producing pressure increments on different areas of the skins in a direction generally normal to the surfaces thereof thereby to continuously flex the skins, valve means for controlling the flow of the reagent, and thermostatically-controlled heating means for the reagent.

2. Apparatus, for use in treating skins, comprising a chamber in which the skins are to be placed in a stack, a header tank for a reagent to be used in the treatment, means included in a closed circuit for propelling the reagent through the chamber in a direction from edge to edge of the skins in the stack, means for controlling said propelling means to vary the speed and pressure of the reagent flow, means for reversing the direction of reagent flow through said chamber so that different portions of the peripheries of the skins in the stack are presented to the reagent at entry to the chamber, means for producing pressure increments on different areas of the skins in a direction generally normal to the surfaces thereof thereby to continuously flex the skins, valve means for controlling the flow of the reagent, and thermostatically-controlled heating means for the reagent.

3. Apparatus, for use in treating skins, comprising a chamber, a rotary basket in said chamber in which the skins are to be placed in a stack, a header tank for a reagent to be used in the treatment, means for propelling the reagent through the chamber in a direction from edge to edge of the skins in the stack, means for controlling said propelling means to vary the speed and pressure of the reagent flow, means for rotating said basket so that different portions of the peripheries of the skins in the stack are presented to the reagent at entry to the chamber, means for producing pressure increments on different areas of the skins in a direction generally normal to the surfaces thereof thereby to continuously flex the skins, valve means for controlling the flow of the reagent, and thermostatically-controlled heating means for the reagent.

4. Apparatus, for use in treating skins, comprising a chamber in which the skins are to be placed in a stack, a header tank for a reagent to be used in the treatment, means for propelling the reagent through the chamber in a direction from edge to edge of the skins in the stack, means for controlling said propelling means to vary the speed and pressure of the reagent flow, means for relatively presenting different portions of the peripheries of the skins in the stack to the reagent at entry to the chamber, a plurality of reciprocating rams in one wall of said chamber, a resiliently compressible and expansible bed at an opposite wall of said chamber, means for reciprocating said rams so that said rams and said bed conjointly apply pressure increments to and relieve the pressure increments from different areas of the skins in a direction generally normal to the surfaces thereof thereby to continuously flex the skins, valve means for controlling the flow of the reagent, and thermostatically-controlled heating means for the reagent.

5. Apparatus, according to claim 1, incorporating a compressor-exhauster and valve means whereby air can be delivered under pressure to, or withdrawn from, the chamber at either of the connections of the latter to the reagent-circulating system.

6. Apparatus, for use in treating skins, comprising a chamber in which the skins are to be placed in a stack, a header tank for a reagent to be used in the treatment, means for propelling the reagent through the chamber in a direction from edge to edge of the skins in the stack, means for controlling said propelling means to vary the speed and pressure of the reagent flow, means for relatively presenting different portions of the peripheries of the skins in the stack to the reagent at entry to the chamber, means for producing pressure increments on different areas of the skins in a direction generally normal to the surfaces thereof thereby to continuously flex the skins, valve means for controlling the flow of the reagent, thermostatically-controlled heating means for the reagent, electro-magnetically actuatable means, respectively, for controlling said reagent propelling means, the means for relatively presenting different portions of the peripheries of the skins to the entering reagent, the pres-

sure increment producing means, and the valve means, and an electric master time-controlled unit for controlling said electro-magnetically actuatable means in timed sequential relationship.

5 7. Apparatus, for use in treating skins, comprising a chamber in which the skins are to be placed in a stack, a header tank for a reagent to be used in the treatment, a reagent inlet, comprising a plurality of spaced ducts, for said chamber, a reagent outlet for said chamber, means for propelling the reagent through the chamber in a direction from edge to edge of the skins in the stack, means for controlling said propelling means to vary the speed and pressure of the reagent flow, said spaced inlet ducts distributing the flow of reagent relatively widely across said chamber, means for relatively presenting different portions of the peripheries of the skins in the stack to the reagent at entry to the chamber, means for producing pressure increments on different areas of the skins in a direction generally normal to the surfaces thereof to flex the skins, valve means for controlling the flow of the reagent, and thermostatically-controlled heating means for the reagent.

PAUL POSER.
